WILBUR G. LAIRD, OF PLEASANTVILLE, NEW YORK, ASSIGNOR TO DOHERTY RESEARCH COMPANY, OF NEW YORK, N. Y., A CORPORATION OF DELAWARE

GAS HOLDER

Continuation of application Serial No. 93,113, filed March 8, 1926. This application filed February 6, 1931. Serial No. 513,871.

This invention relates to gas holders and more particularly to those of the water sealed single lift type. This invention was originally described in my previously filed application Ser. No. 93,113 filed March 8th, 1926, of which this is a full continuation.

The type of gas holder in most common use, consists of a tank or water reservoir in which one or more lifts are constructed in such a manner that as the gas is introduced into the holder the lift is elevated and the gas is prevented from escaping by means of the liquid seal at the lower edge of the lift.

In a single lift holder, the lift comprises a single inverted bell which is open at the bottom or liquid-sealed end and is closed at the top by a crown curved to the form of a section of a sphere and made gas-tight throughout. As gas is introduced and withdrawn from the holder, this bell or lift rises and falls and is supported by the gas pressure within the holder; the bottom of the lift being sealed against gas escape by the liquid seal provided by the water tank or liquid reservoir.

In order to confine the lift to a vertical movement alone and prevent tipping, it is customary to provide a guide-frame or heavy structural steel frame work which usually is attached to the side of the tank and which serves to hold the lift in a vertical position throughout its travel. The lift is provided with suitable guide-rollers held by goose-necks attached to the crown of the lift and which engage guide-rails attached to the guide-frame, or as in the usual practice engage a vertical member of the guide-frame itself. Similar rollers are attached to the lower edge of the lift and engage guide-rails installed against the inside wall of the tank. The guide-frame must be sufficiently strong and rigid to prevent any normal tendency of the lift to tip out of line when in an elevated position and, furthermore, must be strong enough to withstand all wind strains against both itself and the lift which it guides. The

height of the guide-frame is determined by the depth of the lift and its vertical travel.

The primary object of the present invention is to provide a means whereby the vertically movable lift may be held in proper alignment without employing the usual heavy and expensive guide-frame.

Another object of the invention is to provide a guiding means which will permit a lift to be installed in practically any type of tank without requiring special foundation work or other alterations for accommodating a special guide-frame.

Another object of the invention is to provide a means for guiding the lift of a holder, which may be contained within the holder and protected from climatic conditions involving atmospheric oxidation and corrosive reactions.

Another object of the invention is to provide a means for guiding a gas holder, which will permit of quick and easy alignment of the lift in the event of foundation settlement and tank warpage.

Further objects of the invention are to provide a guiding means for a gas holder that is simple and inexpensive to install; is easy to keep in proper adjustment and repair; and makes the holder unit more attractive in appearance.

With these and other objects in view the invention consists in the improved method of constructing a gas holder as hereinafter illustrated and claimed.

Fig. 1 is a plan view with parts in section of a single-lift gas holder embodying a preferred form of the invention, and

Fig. 2 is a vertical sectional view of the holder shown in Fig. 1.

The means or mechanism for guiding a gas holder in the present invention has been illustrated as applied to the common type holder consisting of hollow bell, or lift, mounted in a tank of water. The lift moves vertically up and down in a tank 12,

gas is introduced under the lift 10 through a pipe 14 and is removed through a pipe 16. The bottom of the lift is sealed against the escape of gas by a body of water in the tank 5 12, the level of the water being indicated at 18.

As the gas moves into and out of the lift, the lift rises and falls, the weight of the lift being supported by the body of gas within. 10 It will be apparent therefore, that the lift must be accurately guided in order that it may operate freely and effectively. Spacing rollers 19 (Fig. 1) mounted on the inner rim of tank 12 between the tank and the lift serve 15 to hold the outer periphery of the lift in properly spaced relation to the inner periphery of the tank.

The guiding means of the present invention consists of a series of flexible cables, ropes, 20 chains or other flexible members which are mounted within the tank and lift and attached to the tank and lift so that they guide the lift and constrain it to move in a vertical path. To accomplish this cables 20 are arranged in pairs around the periphery of the lift and preferably each pair is mounted to extend across the lift diametrically. Each pair of cables is the same and each pair is mounted in the tank and lift in the same way so 25 that only one pair of cables will be described. One cable of a pair is attached to a hanger 22 near the rim of the tank then passes down the tank under a pulley 24 then up and over a pulley 26 mounted under the crown of the 30 lift, then across the lift and over a pulley 28 on the opposite side of the lift from the pulley 26, then down and under a pulley 30 mounted on the lower edge of the lift vertically below the pulley 28, then up to a bracket 32 mounted on the rim of the tank at a 35 position substantially diametrically opposite from the hanger 22. At the point where the cable above described emerges from the water to be attached to the bracket 32 the cable may 40 be in the form of a chain as shown, which will better withstand the corrosive action that occurs at the water's surface. The connection of the cable with the bracket 32 consists of a bolt 34 passing through a heavy compression 45 spring 36 which acts to hold the cable taut. The other cable of the pair is mounted in the tank and lift in the reverse position from the above described cable and moves parallel to it. For example, the other cable of the pair 50 has one end attached to a hanger 23 fixed to the rim of the tank adjacent the bracket 32, then it passes down under a pulley 38 in the bottom of the tank, then up over a pulley 40 adjacent the pulley 28, then over a pulley 42 55 adjacent the pulley 26, then down under a pulley 44 mounted on the bottom of the lift and then up to a bracket 46, to which it is connected by bolt 34.

In the drawing only two pairs of cables 60 have been illustrated but it is apparent that

any desired number of pairs may be used and the pairs would preferably be uniformly distributed around the inner periphery of the lift. It is not necessary that the cables be positioned on the diameter of the lift as illustrated in the drawing. When the lift moves up and down the ends of the cables remain fixed and the cable moves on the pulleys 26, 28, 30, 40, 42 and 44 to adjust them for the different positions of the lift. The cables 70 constrain the wall of the lift to move in a vertical plane. The side pressure of the wind against the side of the lift is effectively resisted by the arrangement of the cables in passing under the pulley attached to the lower 75 edge of the lift.

The pulleys 24 and 38 act only as guides for the cables since the cables do not move in these pulleys as the lift moves up and down. These pulleys however are useful in changing, 80 inspecting or repairing cables. For example, a new cable may be attached to an old guide cable and then pulled into the position occupied by the old guide cable while the old guide cable is being removed. This new cable 85 may then be used for replacing the guide cable or may be withdrawn again if the old cable is found to be in good condition. This operation may be carried on without entering the tank or lift.

With the above described apparatus the guide cables are housed entirely within the tank and lift and are thus protected from atmospheric oxidation, rains, snow, the sun and other conditions which tend to corrode and 90 interfere with the proper operation of machinery.

The bolts 34 provide a means by which the cables may be adjusted to support the lift in any desired position and to constrain it to move in the desired position.

The invention having been thus described, what is claimed as new is:

1. In a gas holder, a tank arranged to provide a body of sealing liquid, a closed bell 11 movably mounted in the tank with its wall arranged to move adjacent the wall of the tank in the sealing liquid so as to trap gas within the bell above the sealing liquid, means to introduce gas into and remove gas 11 from said bell and flexible cables secured to the tank and movably mounted wholly within said tank and bell for supporting and guiding said bell in its upward and downward movement in the tank.

2. In a gas holder, a tank, a closed bell 12 movable in the tank, and a guide means for the bell comprising cables arranged in pairs movable in parallel diametrically across the bell and distributed around the periphery of the bell, the ends of the cables being fixed to the tank and the cables movable over pulleys attached to the bell so arranged as to constrain the wall of the bell to move in a vertical path.

3. In a gas holder, a tank, a closed bell movably mounted in the tank, and a guide means for the bell comprising flexible cables movably mounted on pulleys on the inside 5 of the said bell, and the ends of the cables fixed to said tank, one of said ends being positioned in the upper portion of the tank adjacent the upper limit of movement of the bell in the tank and the other end of the 10 cables being fixed in position near the bottom of the tank, said cables being arranged to constrain the wall of the said bell to move in a vertical path as it moves up and down in the tank.
- 15 4. In a gas holder, a tank, a gas storage lift movably mounted in the tank and a guide means for the lift comprising flexible cables mounted wholly on the inside of the tank and lift in pairs distributed around the periphery of the lift, the opposite ends of each of the said cables being secured to the tank, and each cable being guidably connected to the periphery of the lift respectively at diametrically opposite sides of the lift, one cable 20 of each pair supporting the lower edge of the lift at one side, and the other cable of the pair supporting the lower edge of the lift at its opposite side.
- 25 5. In a gas holder, a tank, a lift movably mounted in the tank and a guide means for the lift comprising flexible cables movably mounted on the inside of the lift in pairs and distributed around the periphery of the lift, one end of each cable being fixed within the 30 tank and the other end of the cable being yieldably secured to the upper rim of the tank at a point opposite the point of attachment of the first end of the cable, one cable of the pair supporting the lift at one side, and the other cable supporting the lift at a 35 diametrically opposite side.
- 40 6. In a gas holder, a tank, a lift movable in the tank and a guide means for the lift comprising flexible cables movably mounted on the inside of the lift in pairs and distributed around the inner periphery of the lift, one end of each cable being fixed within the 45 tank and the other end of the cable being yieldably secured to the upper rim of the tank at a point opposite the point of attachment of the first end of the cable, one cable of each pair arranged to pass over a 50 pulley mounted on the lower edge of the lift on one side, then passing over pulleys 55 mounted adjacent the inner side of the roof of the lift and then down to and attached to the tank at a point opposite the said pulley on the lower edge of the lift, the other cable of the pair passing over a pulley mounted on the lower edge of the lift at a point diametrically opposite the first mentioned pulley on the lower edge of the lift, then over pulleys adjacent the first mentioned pulleys 60 mounted on the inner side of the roof of the lift and then down to the tank at a point 65
- adjacent said first mentioned pulley on the bottom of the lift.
7. In a gas holder, a tank, a lift movably mounted in the tank and a guide means for the lift comprising a plurality of flexible cables 70 movably mounted within said tank and lift for supporting and guiding the lift, each cable having one end attached to the rim of the tank, then passing down under a pulley secured to the bottom of the lift, then up parallel to the wall of the lift and across the lift immediately under the roof thereof, then over a pulley and down to the tank and under a pulley attached on the bottom of the tank, then up to a point of attachment 75 at the rim of the tank in a position opposite the attachment of the first end of the cable.
8. In a gas holder, a tank arranged to provide a body of sealing liquid, a gas storage lift 80 movably mounted in the tank with its side walls dipping into the sealing liquid so as to trap gas within the lift above the sealing liquid, and guide means for the lift comprising plurality of flexible cables each operatively connected at horizontally and vertically spaced points to the tank and at horizontally spaced points to the upper and lower parts of the lift and mounted wholly within 85 said tank and lift.
9. In a gas holder, a tank arranged to provide a body of sealing liquid, a gas storage lift 90 movably mounted in the tank with its side walls dipping into the sealing liquid so as to trap gas within the lift above the sealing liquid, and guide means for the lift comprising a plurality of flexible cables each 95 guidably connected to the lift at horizontally spaced points around its periphery, each cable having its ends secured respectively to the top and bottom of the tank and being movable intermediate its ends over pulleys attached respectively to the upper and lower parts of the lift on the interior thereof.
10. In a gas holder, a tank arranged to provide a body of sealing liquid, a lift movably 100 mounted in the tank with the lower part of its outer wall arranged to dip into the sealing liquid so as to trap gas within the lift above the sealing liquid, and guiding means for the lift comprising a series of guide cables 105 disposed at spaced points around the periphery of the lift, each cable being operatively connected to the tank at horizontally spaced points on its periphery and also operatively connected to the top and bottom of the lift 110 at points substantially in line vertically with the nearest points of attachment to the tank, said cables being mounted within the tank and lift and arranged to constrain the movement of the lift to a fixed vertical path.
11. In a gas holder, a tank arranged to provide a body of sealing liquid, a gas storage lift 115 movably mounted in the tank with its side walls dipping into the sealing liquid so as to trap gas within the lift above the sealing 120 liquid.

liquid, guide means for the lift comprising flexible cables each operatively connected at horizontally spaced points to the upper and lower parts of the tank and to the upper and lower parts of the lift and mounted within said tank and lift, and spacing means for maintaining a properly spaced relation between the outer periphery of the lift and the inner periphery of the tank as the lift moves up and down.

10 In testimony whereof I affix my signature.
